UNITED STATES PATENT OFFICE

JACOB DARRE JENSSSEN, OF NEW YORK, N. Y., ASSIGNOR TO G. D. JENSSSEN COMPANY,
OF NEW YORK, N. Y.

MANUFACTURE OF SULPHITE ACID LIQUOR

Application filed July 7, 1930. Serial No. 466,175.

The invention relates to the manufacture of sulphite acid liquor, as described in the present specification and illustrated in the accompanying drawing that forms part of 5 the same.

The invention consists essentially in the means employed for strengthening the free acid liquor resulting from combining the elements in association with the aforesaid means 10 as pointed out in the claim for novelty following a description in detail of the preferred form of the invention.

The objects of the invention are to produce an acid liquor that will not materially vary 15 in regard to the proportions of its contents particularly in respect to lime quantities which are apt to change considerable under different weather conditions as for example, in the hot weather, the disintegration of the 20 lime is greatly increased while in the cold weather the lime resists the attack of the gases so that the maximum quantity of lime absorbed in the water with the gases on warm days is much in excess of the requirement, 25 while on cooler days, the maximum quantity absorbed is approximately correct, therefore to regulate these quantities insures an even cooking liquor and better pulp; to maintain the continuity of the process in the production 30 of acid liquor, that is to say, to introduce in the known methods of making acid liquor an auxiliary means whereby the direction of the flow is so adjusted as to divert the gas in order to obtain two distinct operations under 35 different conditions; to utilize existing systems to the greatest extent possible and at the same time adjust the differences in regard to the contents without materially adding to the cost of production; and generally 40 to provide for cooking purposes in pulp processes an acid liquor of superior quality notwithstanding the natural fluctuations due to temperature conditions.

The drawing is a diagrammatic view showing 45 the essential elements contributory to the carrying out of this invention.

Referring to the drawing, the numeral 15 indicates the tower or tank forming the receptacle in which the ingredients are combined to produce an acid liquor.

Usually these ingredients are lime and SO₂ gas emanating from the sulphur burner indicated by the numeral 16. This gas usually goes through various devices such as coolers and flows along within the gas inlet feed pipe 55 17 to the tower or tank 15 herein shown as the absorption receptacle and the valve 18 is introduced in the gas inlet pipe line towards the receptacle end.

The auxiliary receptacle 19 contains inert 60 material 20, such as blocks of hardwood or other material adapted to resist the attack of the gases, this inert material being supported on the grate 21 and arranged in a pile of broken or separated pieces which will permit the trickle of the acid liquor there through and through the grate therebelow.

The gas inlet pipe line 22 taps the pipe line 17 before it reaches the valve 18 and this pipe line 22 extends to the inlet 23 near to 70 the lower end of the auxiliary receptacle 19.

The pressure blower 24 is introduced in the pipe line 22 before it reaches the auxiliary receptacle 19, thus forcing in the gas at a considerable pressure below the grate 21.

Above the inert material the return pipe line 25 extends from the gas outlet 26 and leads to the pipe line 17 and communicates therewith between the valve 18 and the inlet to the receptacle 15.

The valve 27 is introduced in the pipe line 25 adjacent to the auxiliary receptacle and this is a very important valve, as by means of this valve the pressure is very finely regulated within the auxiliary receptacle.

Therefore the absorption of gas is carefully adjusted to the needs of the occasion.

The pipe line 28 leads into the receptacle 15 from a suitable water supply and the pipe line 29 leads from the bottom of the receptacle 15 to the free acid liquor inlet 30 at the top of the receptacle 19, consequently the water which has entered the receptacle 15 after it has become charged with lime and SO₂ to the extent required flows through to 90 the pipe line 29 in the form of free acid liquor into the auxiliary reservoir 19 and from there trickles down through the inert material meeting the rising gases which are forced into the auxiliary receptacle below the 100

grate and held back therein at the desired pressure and picks up the quantity of SO_2 according to the strength required and falls down below the grate where it passes out.

- 5 The looped pipe line 31 extends from the outlet 32 of the auxiliary reservoir downwardly and upwardly to the storage tank 33 and thus at all times a water seal is provided in the trap 34 at the bottom of this outlet 10 pipe line, the upwardly extending leg 35 to the storage tank being also filled with acid liquor to complete the seal, thereby preventing the loss of gas from the auxiliary tank through the outlet 32.
- 15 The valve 36 is provided in the pipe line 31 if required. The pump 37 and a valve 38 are also introduced in the pipe line 29 one on either side of the pipe line 39, which forms the direct passage from the tank 15 to the 20 storage tank 33, when it is desired to cut out the auxiliary tank or tower 19.

The valve 40 is also introduced in the pipe line 39 so as to effectively cut out the storage tank when the delivery is entirely to the auxiliary receptacle 19. The valve 47 is introduced in the pipe line 22 for obvious purposes.

The operation of this invention has been fairly well described in explaining the uses 30 of the several elements, but briefly it may be stated that the SO_2 gas is prepared in the most acceptable manner and flows through a main pipe line to the tank, tower or receptacle 15 where lime is being treated in the preferred manner.

The acid liquor produced in this receptacle 15 falls to the bottom and in carrying out this invention is transferred by an outlet pipe line to the top of an auxiliary tank, tower or receptacle 40 where it trickles through inert material and meets a gas, which also comes from the main pipe line, but through a branch passage which taps the main pipe line, a pressure blower being introduced to give 45 greater force to the delivery of gas into the auxiliary receptacle below the grate.

Meanwhile the valve 27 has been carefully adjusted so as to obtain within the receptacle 19 the desired pressure for it is advisable to 50 have a considerable pressure within this auxiliary receptacle in order that a considerable quantity of SO_2 gas may be absorbed, but at the same time, it is necessary to have an outlet for the gas as the nitrogen is not 55 useful and must find an outlet, but this nitrogen carries away with it a considerable quantity of oxygen and sulphur gas and this is again useful and is returned to the receptacle 15 to reinforce the gas already passing 60 thereinto from the main line of piping, the nitrogen finally passing off at the upper end of the main receptacle.

What I claim is:—

In the manufacture of acid liquor, a main 65 line gas feed pipe leading from a source of

supply of SO_2 gas, a primary receptacle towards its lower end connected to said gas pipe and at its upper end to a water supply and containing a lime element, an auxiliary receptacle connected at the upper end to the 70 lower end of the aforesaid receptacle and containing acid resisting inert material in irregular pieces, a supplementary feed pipe tapping the main gas feed pipe and communicating with the lower portion of said auxiliary receptacle below said inert material and a pressure blower introduced therein, a gas exhaust pipe connecting the upper end portion of the auxiliary receptacle with the main feed pipe adjacent to the primary receptacle, a storage receptacle, a discharge pipe having a trap portion and connecting the lower end of the auxiliary receptacle to said storage tank, a discharge pipe from the liquid outlet of the primary receptacle to said storage tank and valves introduced in 80 all of said pipes and connections for adjusting and regulating the flows.

Signed at New York, N. Y., this 11th day 85 of June, 1930.

JACOB DARRE JENSSSEN.
